DESIGN FOR A GLOVE

Camille V. Perrin, New York, N. Y.

Application May 13, 1936, Serial No. 62,609

Term of patent 3½ years

To all whom it may concern:

Camille V. Perrin, a citizen of France, residing in Manhattan, county of New York and State of New York, have invented a new, original, and ornamental Design for a Glove, of which the following is a specification, reference being had to the accompanying drawing, forming part thereof, wherein,

The characteristic feature of my design resides in the attached bracelet on the wrist portion of the glove, as shown.

I claim:

The ornamental design for a glove, substantially as shown, and described.

CAMILLE V. PERRIN.
